UNITED STATES PATENT OFFICE.

ARTHUR W. SMITH, OF NEW YORK, N. Y., ASSIGNOR, BY MESNE ASSIGNMENTS, TO REMINGTON TYPEWRITER COMPANY, OF ILION, NEW YORK, A CORPORATION OF NEW YORK.

TYPE-WRITING MACHINE.

1,060,292.

Specification of Letters Patent.

Patented Apr. 29, 1913.

Application filed January 4, 1911. Serial No. 600,758.

To all whom it may concern:

Be it known that I, ARTHUR W. SMITH, citizen of the United States, and resident of the borough of Manhattan, city of New York, in the county of New York and State of New York, have invented certain new and useful Improvements in Type-Writing Machines, of which the following is a specification.

10 My invention relates to typewriting machines and more particularly to speed controlling mechanism for the carriage, to prevent the latter from traveling with undue speed when it is released from the control 15 of the escapement mechanism, as in tabulating operations, for example.

One of the main objects of my invention, generally stated, is to provide comparatively simple and efficient mechanism for 20 the purposes set forth, and one in which the speed controlling mechanism is normally operatively connected with the carriage, though said mechanism is ineffective to retard the carriage but may be rendered effective at will; as for instance when a tabulating operation takes place.

To the above and other ends which will be hereinafter described the invention consists in the features of construction, combinations of devices and arrangements of 30 parts to be hereinafter set forth and particularly pointed out in the appended claims.

In the accompanying drawings wherein like reference characters indicate corresponding parts in the various views, Figure 1 is a fragmentary central vertical sectional view of one form of typewriting machine embodying my invention; only so much of said machine being shown as is necessary to illustrate my invention in its embodiment therein. Fig. 2 is a fragmentary detail perspective view showing a portion 40 of the tabulating mechanism. Fig. 3 is a fragmentary detail view showing the means by which the speed controlling mechanism is rendered effective. Fig. 4 is a detail vertical sectional view showing a portion of the carriage controlling mechanism. Fig. 5 is a fragmentary detail vertical sectional view of a portion of the tabulating mechanism.

I have shown my invention embodied in the present instance in a No. 10 Remington machine and operating in conjunction with 55 tabulating or column selecting mechanism

such as is embodied in that machine, and similar to that disclosed in the patent of Clio B. Yaw, No. 984,338, dated February 14, 1911. It should be understood, however, that the invention may be embodied in various styles of typewriting machines and may be employed in connection with various forms of tabulating mechanism.

The frame of the machine comprises a base 1, corner posts 2 and a top plate 3. A carriage 4 is provided with front and rear grooved cross bars 5 which receive anti-friction balls or rollers 6, which support the carriage in its movement from side to side of the machine over the top plate 3. These anti-friction rollers are likewise received in fixed oppositely grooved rails 7 supported on upwardly extending lugs 8 fixed to the top plate of the machine. A rotative platen 9 is supported by the carriage; the platen and manner of supporting it being conventionally represented in the present instance. Rearwardly extending arms 10 are pivoted at 11 to upwardly extending lugs on the carriage and are fixed at their rear ends by screws 12 to a feed rack 13. The feed rack meshes with a pinion 14 fixedly mounted on the forward end of a shaft which turns in a bearing 15 secured to the top plate of the machine. The rear end of the shaft has an escapement wheel 16 connected thereto for coöperation with the usual key controlled carriage feed mechanism, not shown.

It will be understood that when the feed rack 13 is moved upwardly out of engagement with its coöperative feed pinion, the carriage is freed from control of the escapement mechanism and is free to be propelled from right to left by the usual spring drum 17 connected to the carriage by a strap or band 18 fixed at one end to the drum and at its opposite end to an arm 19 fixed to the carriage.

Rearwardly extending bracket arms 20 project from the carriage and support a column stop bar 21 formed with teeth 22 on opposite sides thereof for the reception of bifurcated column stops 23 received in the interdental spaces between the teeth on the column stop bar. Rearwardly projecting contact portions 23a on the column stops are adapted to coöperate with stops 24, 25, 26, 27 and 28 on a stop head 29 fixed at the upper end on a vertically disposed shaft 30 mounted to turn in bearings in the frame of

the machine. Thus the shaft passes through an opening in the top plate and turns in and is supported by a bearing member 31 (Fig. 5) having a flange 32 which is fixed to the top plate of the machine. A coiled spring 33 is contained within the bearing 31 and surrounds the shaft 30. One end of this spring is fixed to the shaft by being received in a groove 34 therein, the other end of the spring being received in a slot 35 in the bearing 31. In this manner one end of the spring is fixed to the bearing member and the other end is fixed to the shaft 30 and tends to rotate the shaft so as to normally maintain the portion 36 of the stop head, which is without stop projections, opposite the column stops, so that normally the carriage is free to travel and carry the column stops past the stop head 29.

20 The lower end of the shaft 30 is provided with a pinion 37 which meshes with rack teeth 38 on a slide bar 39 mounted to move longitudinally in grooved bearing openings 40 of a bracket 41 secured to the frame of the machine. The slide bar 39 is provided with an upwardly projecting pin 42 near the right-hand end thereof, which pin is received in a slot or cut-out 43 in a plate or slide 44. This plate is mounted in grooved bearings in the bracket 41 to slide fore and aft of the machine and is provided with a cam face or edge 44^a at the left-hand end of the slot for coöperation with the pin 42. It will be understood therefore that a rearward movement of the slide 44 from the normal position shown in Fig. 2 will cause the slide 39 to be moved to the right through the coöperation of the cam 44^a with the pin 42. This movement will be transmitted 40 through the rack 38 and pinion 37 to effect a rotative movement of the head 36, in order to bring the first of the stops thereon (24) into the path of the column stops to render the column stops coöperative there- 45 with. A pawl 45 is pivoted to the bracket 41, as indicated at 46. A leaf spring 47 bears down at its free end on top of the pawl 45 and tends to depress the lower engaging tooth (not shown) thereon into engagement with the ratchet teeth (not shown) 50 on top of the slide 39 to hold the slide against return movement after it starts its movement to the right. A downward movement of the pawl is afforded by a forward movement of the plate 44 and a rearward movement of the plate 44 is effective to elevate the pawl 45 through the coöperation of the cam faces 48 and 49 on the plate 44 and pawl 45 respectively. The elevation 55 of the pawl is effective to disengage it from the ratchet teeth of the slide 39 to enable said slide and the stop head 29 to return to normal position.

60 The extent to which the stop head 29 may be rotated by the various column stops de-

termines the selection of the column and the extent of travel of the carriage. The extent of rotative movement of the column stop head is determined by a series of key-actuated slides 50 arranged to slide fore and aft of the machine in grooved bearings in the bracket 41. These slides normally are maintained out of the path of longitudinal movement of the slide 39 and are adapted to be projected across the slot 40, through which the slide 39 moves, and into the path of said slide in its movement from left to right. The effect of a rearward movement of one of the slides 50 is to carry it into the path of movement of the slide 39, and when the travel of the carriage brings the column stops successively into coöperation with the different stops 24, 25, etc., on the stop head 29 the shaft 30 will be rotated to move the slide 39 to the right until it is arrested by contact with the slide 50 which has been moved rearwardly. The projected slide 50 arresting the rotative movement of the stop head causes the carriage to be arrested at the selected columnar position by 90 the coöperation of one of the column stops with one of the stops 24, 25, 26, etc.

95 The slides 50 are controlled by a series of tabulator keys 51 at the key-board of the machine. Each of these tabulator keys is connected to a key stem 52, which is operatively connected with associate angular levers 53, pivoted on a pivot rod 54 fixed to the frame of the machine. Each of the angular levers 53 is connected to a restoring spring 55 and to an actuating link 56 which latter in turn is connected to the associate slide 50. A universal bar 57 extends from one depending arm 58 to the other, these arms being formed as parts of the bar and pivoted on the pivot rod 54. The universal bar is arranged in the paths of the depending arms of the angular levers 53 to be engaged by one of such depending arms at the depression of the associated tabulator key 51. The arms 58 are connected at their lower ends to rearwardly extending links 59 which in turn are connected to depending crank arms 60 on a rock shaft 61. A curved upwardly extending crank arm 62 is likewise fixed to the rock shaft 61 and is connected at its upper end to a link 63 pivoted at 64 to a release lever 65 pivoted at 66 to a bracket fixed to the top plate of the machine. The forward end of the release lever 65 extends beneath the feed rack 13 so that a rocking movement of the shaft 61 is effective to turn the crank arm 62, thereby pulling down on the link 63 and elevating the feed rack 13 to release it from the feed pinion 14 to free the carriage from control of the escapement mechanism. A spring 67 is fixed at one end to a pin 68 and is connected at its opposite end to a crank arm 69 depending from and fixed to the rock shaft 130

61. This spring returns the rock shaft 61 and the various parts connected therewith to normal position. A depending crank arm 70 is pivoted at 71 to a link 72 which in turn is pivoted at 73 to the slide 44, so that the same movement which is effective to release the carriage in the manner hereinbefore described is likewise effective to move the slide bar 39 to the right through the rearward movement of the slide 44, in order to bring the first of the stops (24) on the stop head 29 into position to coöperate with the column stops.

10 The features thus far described form no part of my invention except so far as they are combined with other features to be hereinafter described, and the tabulating mechanism disclosed may therefore be varied at will.

20 I have provided means for controlling the speed of the carriage in its travel during tabulating operations when the carriage is freed from the control of its escapement mechanism and travels in the direction of its feed. The speed-controlling mechanism of my present invention comprises a rack 74 fixed by screws 75 to the bracket arms 20. This rack meshes with a pinion 76 with which it is constantly maintained in engagement. This pinion is fixed to one member of a two-part shaft 77; the two parts of the shaft being united by a threaded connection 78 and by which the two parts of the shaft are maintained rigidly connected to turn together. The upper section of the shaft extends through a bearing opening of the top plate and the lower end of the shaft is received in a stepped journaled bearing 79 in the base 1 of the frame. A long cylindrical drum 80 of comparatively small diameter surrounds the lower section of the vertically disposed shaft 77, and incloses a radiating arm or blade 81 which is fixed to and projects from the shaft. An upper head 82 is secured to the drum by screws 83 received in tapped openings in the head, whereas a lower head 84, in a like manner, is connected to the drum by screws 85. Material is contained within the closed drum 80 for coöperation with the arm or blade 81 which latter, under certain conditions to be herein-after pointed out, may rotate within the drum. Any suitable material may be employed in the drum to offer a resistance to the blade during the relative turning movement between the shaft 77 and drum 80. I prefer, however, to employ shot, as indicated at 80^a, or some such equivalent material for coöperation with the blade. A stop pin, holding or locking device 86 is received at its threaded end in the lower head 84 and projects downward therefrom. This pin, as will be seen from inspection of Figs. 3 and 4, is arranged off to one side of the center of rotation of the drum. The only connection be-

tween the shaft 77 and the drum is through the blade or arm 81 and the material 80^a contained within the drum. The blade 81 coöperates at its upper edge with the upper head of the drum to maintain it against downward displacement on the shaft but a relative movement between the shaft and drum may be effected or the drum and shaft may rotate together, the parts maintaining a fixed relation as they turn together.

70

75

The shaft 77 is rotated or moves in unison with the carriage at all times during the travel of the carriage, whether the carriage receives a backward or forward movement by reason of the constantly maintained gear connection 74—76 between the carriage and shaft 77. Normally, however, this movement of the shaft 77 is ineffective to retard or effect the movement of the carriage, since the drum 80 is normally carried around with the shaft and is ineffective to retard the carriage. When, however, one of the tabulator keys is depressed to release the carriage from control of the escapement mechanism and to throw the tabulator into operation, a rearward movement of the slide 44 is effected. This movement likewise effects a rearward movement of a bracket arm 87 carried by said slide to carry a stop, holding or locking device 88 thereon into the path 95 of the stop pin 86 on the drum 80, as indicated in full lines in Fig. 3. This is effective to hold the drum against rotation while the shaft 77 continues its rotation and causes the arm 81 to rotate within the drum 80, which at this time is maintained fixed. The arm 81 working against the shot 80^a in the fixed drum retards the movement of the carriage and prevents undue shock between the column stops and the stops on the head 29 by which the carriage is arrested. As soon as pressure is released on the depressed tabulator key the carriage is again restored to control of the escapement mechanism and the tabulator is thrown out of operation. At 100 this time the slide 44 is moved forwardly to the position shown in Fig. 2, thereby moving the stop 88 to the dotted line position represented in Fig. 3 and out of the path of the stop pin 86 on the drum, thus releasing the 110 drum and permitting it to rotate freely with the shaft 77, so that no retardation of the carriage is at this time effected.

105

110

115

120

125

130

From the foregoing description it will be understood that the carriage speed-controlling mechanism of my invention comprises two parts, one of which is constantly in operative connection with the carriage to be moved thereby and the other of which is adapted to move with the first mentioned part or to be held against movement therewith; that when the parts in question turn together no retarding effect is produced whereas when a relative movement between the parts is effected the mechanism becomes

operative to retard the carriage in its movement. Moreover, it will be seen that the carriage speed-controlling mechanism is simple in construction, inexpensive to manufacture, effective in use and is not liable to become deranged or broken or to get out of order.

What I claim as new and desire to secure by Letters Patent, is:—

1. In a typewriting machine, the combination of a carriage; and speed-controlling means therefor comprising two members one a drum and the other a member rotative within the drum, a constantly maintained direct geared connection between the carriage and one of said members, means operable at will to hold the other member or to free it to turn with the geared member, and a mass of retarding material contained within said drum and which is effective to retard the relative movement between the two members.

2. In a typewriting machine, the combination of a carriage; and speed-controlling means therefor comprising two members one a drum and the other a member rotative within the drum, a constantly maintained direct geared connection between the carriage and the member which is rotative within the drum, means operable at will for holding said drum or for freeing it to turn with the member which is rotative therein, a mass of retarding material contained within said drum and which is effective to retard the relative movement between the two members; escapement mechanism; and means for releasing the carriage from control of said escapement mechanism and for simultaneously actuating said holding means.

3. In a typewriting machine, the combination of a carriage; a shaft constantly maintained in direct geared connection with the carriage to move in unison therewith; a drum which surrounds said shaft; an arm contained within said drum and carried by said shaft; a mass of retarding material contained within said drum and against which said arm is adapted to work; and key controlled means operable at will for holding the drum against turning movement with the shaft or for freeing the drum to afford a turning movement of the shaft and drum together.

4. In a typewriting machine, the combination of a carriage; a rack carried by the carriage; a pinion which is constantly maintained in mesh with said rack; a shaft which carries said pinion; an arm on said shaft; a drum which surrounds said arm and shaft; a stop contained within said drum; a stop on the drum; and a key controlled stop movable into and out of the path of said stop on the drum to lock said drum against rotation with the shaft or to afford a free movement of the drum and shaft together.

5. In a typewriting machine, the combination of a carriage; escapement mechanism therefor; tabulator mechanism; carriage releasing mechanism for freeing the carriage from control of the escapement mechanism when the tabulator mechanism is operated; a rack carried by the carriage; a pinion constantly maintained in mesh with said rack; a shaft which carries said pinion; an arm on said shaft; a drum which loosely surrounds said shaft and said arm; a stop contained within said drum; a stop on said drum; and a cooperative stop which is automatically moved into the path of the stop on the drum to prevent a rotation thereof with the shaft when the carriage is released and which is withdrawn from the path of the stop on the drum when the carriage is again restored to the control of the escapement mechanism so that the drum is free to rotate with the shaft.

6. In a typewriting machine, the combination of a paper carriage, escapement mechanism therefor, mechanism for releasing the carriage from the escapement for rapid movement, a fixed rack on the carriage, a pinion constantly engaging said rack, a shaft carrying said pinion and also a blade or arm, a drum surrounding said shaft and blade or arm and containing resisting material; the shaft, blade or arm, drum and resisting material all rotating together during letter space movements of the carriage, and means connected with said carriage releasing mechanism adapted to engage and hold said drum when the carriage is released, whereby the blade or arm on the constantly rotating shaft is adapted to act on the resisting material within the drum and cause retardation of the carriage.

7. In a typewriting machine, the combination of a carriage; escapement mechanism including a feed pinion and a feed rack movable into and out of mesh with said pinion; a carriage releasing device for disengaging the feed rack from the pinion to release the carriage from control of the escapement mechanism; and carriage retarding mechanism comprising a second rack carried by the carriage, a speed controlling member constantly maintained in mesh with said second rack to move in unison with the carriage during the movement of the latter in a letter-feed direction, a second carriage speed controlling member which normally moves with said first mentioned controlling member and which is normally ineffective therefore to retard the carriage, and key controlled means for arresting said second controlling member when the feed rack is disengaged from its feed pinion, thereby rendering the controlling members effective to control the speed of the carriage.

8. In a typewriting machine, the combination of a carriage; escapement mechanism

- including a feed pinion and a feed rack movable into and out of mesh with said pinion; a carriage releasing device for disengaging the feed rack from the pinion to release the carriage from control of the escapement mechanism; carriage retarding mechanism comprising a second rack carried by the carriage, a speed controlling member constantly maintained in mesh with said second rack to move in unison with the carriage during the movement of the latter in a letter-feed direction, a second carriage speed controlling member which normally moves with said first mentioned controlling member and which is normally ineffective therefore to retard the carriage; tabulator mechanism; means controlled by said tabulator mechanism to actuate said carriage releasing device when the tabulator mechanism is actuated; and means operated by an actuation of the tabulator mechanism for arresting said second controlling member, thereby rendering the controlling members effective to control the speed of the carriage when it is released from control of the escapement mechanism.
9. In a typewriting machine, the combination of a carriage; escapement mechanism including a feed pinion and a feed rack movable into and out of mesh with said pinion; a carriage releasing device for disengaging the feed rack from the pinion to release the carriage from control of the escapement mechanism; and carriage retarding mechanism comprising two members one a drum and the other a member rotative within the drum, a constantly maintained direct geared connection between the carriage and one of said members, means operable when the carriage is released for holding the other member and for freeing it to turn with the geared member when the feed rack is reengaged with its feed pinion, and a mass of retarding material contained within said drum and which is effective to retard the relative movement between the two controlling members.
10. In a typewriting machine, the combination of a carriage; escapement mechanism including a feed pinion and a feed rack movable into and out of mesh with said pinion; a carriage releasing device for disengaging the feed rack from the pinion to release the carriage from control of the escapement mechanism; and carriage retarding mechanism comprising two members one a drum and the other a member rotative within the drum, a constantly maintained direct geared connection between the carriage, and the member which is rotative within the drum, means operable on the release of the carriage for holding said drum and for freeing it to turn with the member which is rotative within the drum when the feed rack is reengaged with its feed pin-
- ion, and a mass of retarding material contained within said drum and which is effective to retard the relative movement between the two controlling members.
11. In a typewriting machine, the combination of a carriage; escapement mechanism including a feed pinion and a feed rack movable out of mesh with said pinion to release the carriage from control of the escapement mechanism; carriage retarding mechanism comprising a shaft constantly maintained in direct geared connection with the carriage to move in unison therewith, a drum which surrounds said shaft, an arm contained within said drum and carried by said shaft, a mass of retarding material contained within said drum and against which said arm is adapted to work, and key controlled means operable at will for disengaging said feed rack and simultaneously holding the drum against turning movement with the shaft and for effecting a reengagement of the feed rack with its feed pinion and simultaneously freeing the drum to afford a turning movement of the shaft and the drum together.
12. In a typewriting machine, the combination of a carriage; escapement mechanism including a feed pinion and a feed rack movable into and out of mesh with said pinion; a carriage releasing device for disengaging the feed rack from the pinion to release the carriage from control of the escapement mechanism; and carriage retarding mechanism comprising a second rack carried by the carriage, a pinion which is constantly maintained in mesh with said second rack, a shaft which carries said pinion, an arm on said shaft, a drum which surrounds said arm and shaft, shot contained within said drum, a stop on the drum, and a key controlled stop movable into and out of the path of said stop on the drum to lock the drum against rotation with the shaft or to afford a free movement of the drum and shaft together, the key controlled stop being moved into the path of the stop on the drum when the carriage releasing device is actuated to disengage the feed rack and being moved out of the path of the stop on the drum when the feed rack is reengaged with its feed pinion.
13. In a typewriting machine, the combination of a carriage; escapement mechanism including a feed pinion and a feed rack movable into and out of mesh with said pinion; a carriage releasing device for disengaging the feed rack from the pinion to release the carriage from control of the escapement mechanism; carriage retarding mechanism comprising a second rack carried by the carriage, a pinion constantly maintained in mesh with said second rack, a shaft which carries said pinion, an arm on said shaft, a drum which loosely surrounds said shaft

and said arm, shot contained within said drum, a stop on said drum, a coöoperative stop which is automatically moved into the path of the stop on the drum to prevent a rotation thereof with the shaft when the feed rack is disengaged by said releasing device and which is withdrawn from the path of the stop on the drum when the feed rack is again reengaged with the feed pinion so that the drum is free to rotate with the shaft; tabulator mechanism, and means controlled by said tabulator mechanism for

moving said coöoperative stop into and out of the path of the stop on the drum and for controlling said releasing device.

15

Signed in the borough of Manhattan, city of New York, in the county of New York and State of New York, this 3rd day of January A. D. 1911.
